UNITED STATES PATENT OFFICE.

ALBERT C. JOHNSON, OF BALTIMORE, MARYLAND.

ORE-ROASTING FURNACE.

SPECIFICATION forming part of Letters Patent No. 786,905, dated April 11, 1905.

Application filed February 4, 1904. Serial No. 191,978.

To all whom it may concern:

Be it known that I, ALBERT C. JOHNSON, a citizen of the United States, residing at Baltimore, in the State of Maryland, have invented 5 certain new and useful Improvements in Ore-Roasting Furnaces; and I do declare the following to be a full, clear, and exact description of the invention, such as will enable others skilled in the art to which it appertains to 10 make and use the same, reference being had to the accompanying drawings, and to the letters of reference marked thereon, which form a part of this specification.

This invention relates to new and useful improvements in ore-roasting furnaces and driers; and the object of the invention is to 15 generally improve upon the form of apparatus embodied in my Patent No. 715,080 and to render more efficient this type of apparatus. 20 More specifically, the present invention consists in the provision of a rocking or tilting furnace of any suitable shape with a horizontal axis and provided with a series of inclined shelves or beds arranged alternately within 25 the furnace or drier in such a manner that the ore or material to be dried which is deposited upon the upper shelf will move from one side of the shelf to the other as the furnace or drier is tilted and at the same time 30 causing the ores or other material to advance toward the free end of the shelf as the rocking of the furnace is continued, whereby the ore or other material is caused to fall from shelf to shelf until it reaches the exit end of 35 the furnace.

My invention consists, further, in various details of construction and in arrangements of parts, which will be hereinafter fully described and then specifically defined in the appended claims.

I illustrate my invention in the accompanying drawings, which, with the letters of reference marked thereon, form a part of this application, and in which drawings—

45 Figure 1 is a sectional view through a portion of my improved ore-roasting furnace, parts of the invention being shown in elevation. Fig. 2 is an end view. Fig. 3 is a

transverse section on line 3 3 of Fig. 1. Fig. 4 is a side elevation of my furnace, showing 50 in dotted lines the projections or ribs for supporting the arch or lining. Fig. 5 is a cross-sectional view through Fig. 4.

Reference now being had to the details of the drawings by letter, A designates my improved furnace, which I have illustrated in the drawings as being cylindrical in shape, although I do not confine myself to any shape or size. B designates heads to the furnace, which are strengthened and reinforced by 55 means of buck-stays integral with the outer portions thereof. Said heads have flanges B', to which the cylindrical shell is fastened by means of bolts b. One head of the furnace is provided with a shaft C, and to said shaft, 60 which has a flange C', is fastened a pipe D, also having a flange D', which is fastened to the flange C'. Said pipe D has an upwardly-extending portion E, which is angled and 65 communicates with the interior of the furnace intermediate the shelf H and the highest portion of the shell. Through said pipe E, which rocks with the furnace, gases are conveyed away from the furnace into the air or into towers or chambers. In order to give 70 access to the pipe E, a cap E' is fitted over the lower end thereof, which may be easily removed when access is desired to clean out pipes or other purposes.

The heads of the furnace are provided with 75 suitable openings, over which doors N are closed, through which apertures access may be had to the interior of the furnace for building up the same, for repair, or other purposes, each being provided with a sight-aperture, which may be closed by means of a small door. In order to regulate the ingress of air to the furnace, slots or openings K are formed in the heads, which are regulated by means of slides K', held by suitable cleats on the opposite sides of said openings.

The interior of the furnace is provided with a suitable lining of tiling or brickwork Q and is provided with a series of shelves, (designated in the drawings by letters H, H', and H²), which are also made of tiling or brick-

work and which are supported along the inner wall of the furnace upon the ribs or brackets J. (Shown clearly in Figs. 4 and 5 of the drawings.) Said ribs or brackets may be cast upon or bolted to the shell of the furnace and extend from end to end thereof and are disposed at suitable angles for the proper inclination of said shelves or beds. These ribs or brackets form the skewers when brick arches are used and the supports when tiling are used. The shelves or beds, as will be observed in the drawings, are alternately inclined in opposite directions with their alternate ends free, and in Fig. 3 it will be observed that the shelves are formed on the arcs of circles the axes of which are at angles to one another and lengthwise of the furnace. The arrangement of the shelves in the manner illustrated is for the purpose of causing the ore being roasted to be carried from one end of the furnace or shelf to the other as the furnace is alternately rocked in one direction and the other, the ore being caused to travel from the inlet to the exit end of the furnace without the use of any working parts, such as rakes, stirrers, &c., inside the furnace.

In the drawings I have illustrated three shelves or beds running from one head of the furnace to the other, with the exception of the intervening of slight spaces between the free end of a shelf and the adjacent end of the furnace, through which space the ore is allowed to fall from an upper shelf to one immediately below. I have also shown the shelves to be convexed, as illustrated in the sectional view; but they may be flat, and a dividing-wall in the center may be employed, if desired.

Projecting from one head of the furnace, opposite to that from which the gases make exit, is a shaft G, which shaft, as well as the shaft C, is mounted in suitable bearings in the standards I, and projecting from said shaft G is a rocking-arm G', which is adjustably connected to a pitman R, which has pivotal connection with an eccentric-pin R', mounted upon the pinion-wheel R², which is in mesh with a worm S, whereby power is applied to the pinion to rock the furnace through the medium of said arm. Surrounding the shell are metallic bands T, which ride upon the antifriction-rollers W, mounted in suitable brackets underneath the furnace.

At any suitable location, preferably over the highest portion of the upper shelf, is located a hopper F, in which the ore is placed and from which it enters the furnace through the feeding-aperture F'. (Shown in Fig. 1 of the drawings.)

The lowest shelf or bed H² has an inclined exit passage-way H³, which has a door H⁴ pivotally mounted adjacent to its end and which opens automatically for the discharge of the cinder.

The operation of my improved furnace is as follows: Having produced sufficient heat in the furnace by artificial means to ignite the material containing sulfur or other combustible material, the ore is introduced through the hopper and drops upon the upper shelf H. As the furnace tilts slightly in one direction, which would be across the line of the shelf or bed, the ore would fall toward the side or circumference of the furnace in the direction in which the latter is tilted, and as the bed or shelf is disposed at an angle the ore in the opposite tilting movement of the furnace would be caused to advance slightly toward the free end of the shelf H, down the inclined surface thereof. By repeating this back-and-forth rocking movement of the furnace it will be observed that the ore will gradually work off from the first shelf onto the second and thence will be caused to move the length of the furnace before reaching the free end of the shelf H, after which it will fall upon the shelf and finally will make exit through the passage H³ near the lowest portion of the bottom shelf or bed. By this movement of the furnace the ore is constantly kept in motion and advances gradually until it reaches the exit end of the furnace, by which time the ore will be thoroughly roasted.

While I have shown a particular form of roasting apparatus embodying the features of my invention, it will be understood that I may make alterations in the same in various ways as to the size of the furnace, arrangement of the shelves, &c., without in any way departing from the spirit of the invention.

When the apparatus is intended to be used as a drier or for roasting very low-grade ores, it is provided with a fire-box to produce artificial heat.

Having thus described my invention, what I claim as new, and desire to secure by Letters Patent, is—

1. A rocking ore-roasting furnace or drier having a series of shelves the upper surfaces of which are convexed, the axes of which shelves are at angles to one another and lengthwise of the furnace, the alternate ends of said shelves being free, and means for rocking the furnace, as set forth.

2. A horizontally-rotatable ore-roasting furnace or drier having a series of shelves, the axes of which shelves are at inclinations to one another and lengthwise of the furnace, the alternate ends of said shelves being free, and means for rocking the furnace, as set forth.

3. A horizontally-rocking furnace or drier having a series of shelves the upper surfaces of which are convexed, the axes of which shelves are at angles to one another and lengthwise of the furnace, the alternate ends of the shelves being free, and means for rocking the furnace axially, as set forth.

4. A horizontally-rocking ore-roasting furnace or drier having a series of shelves the upper surfaces of which are convexed, the axes of which shelves are at angles to one another 5 and lengthwise of the furnace, thereby providing series of shelves which are alternately inclined in opposite directions, an exit-tube passing through the lower of said shelves and

through the wall of the furnace, and means for rocking the latter, as set forth. 10

In testimony whereof I hereunto affix my signature in presence of two witnesses.

ALBERT C. JOHNSON.
